TWO SIDED SLOW WAVE TRANSMISSION CIRCUIT HAVING A SELECTIVE MODE COUPLER
Charles E. Enderby, Palo Alto, and Richard M. White, Berkeley, Calif., assignors to General Electric Company, a corporation of New York

Filed Apr. 28, 1964, Ser. No. 363,201

4 Claims. (Cl. 333—6)

This invention relates to a structure for coupling electromagnetic waves in a particular mode in a waveguide or the like to and/or from a multi-mode wave transmission or propagation structure.

The selective coupler of the invention has a particular utility as the input and/or output coupling means for the interaction circuit of a traveling-wave tube or the like.

In the well-known traveling-wave tube a beam of electrons is projected by an electron gun closely past an interaction circuit along which an electromagnetic wave is propagated, the beam eventually being intercepted by a collector electrode.

Numerous types of interaction circuits have been proposed for use in such tubes. For example, the well-known helix slow-wave circuit has been widely used. However, the helix circuit is not found practical for higher frequencies and higher power because of small physical size and limited power dissipation. Thus as the trend toward higher power and the use of millimeter and submillimeter waves continues, other types of slow-wave circuits are found more practical. Among these are the following: the ladder circuits as discussed, for example, by R. M. White, C. K. Birdsall and R. W. Grow in "Multiple Ladder Circuits for Millimeter Wavelength Traveling-Wave Tubes," pp. 367-402, Proceedings of the Symposium on Millimeter Waves, Polytechnic Institute of Brooklyn, New York, 1959; the "ring-bar" circuits as discussed, for example, by C. K. Birdsall and T. E. Everhart in "Modified Contra-Wound Helix Circuits for High-Power Traveling-Wave Tubes," pp. 190-204, Trans. IRE PGED, vol. 3, October, 1956; and the "ring-plane" circuits as discussed "for example" by R. M. White et al. in "Additional Information on 'An Interaction Circuit for Traveling-Wave Tubes,'" pp. 1686 and 1687, Proc. IRE, vol. 49, November 1961.

In the use of some versions of these circuits, the thick ladder circuit, the double ladder circuit, the ring-plane circuit as examples, a serious problem arises from the fact that the circuit propagates two modes of nearly equal phase velocities. It is therefore difficult to propagate the electromagnetic wave in the desired mode without exciting the undesired mode.

For example, in the White et al. article entitled "Additional Information on 'A Interaction Circuit for Traveling Wave Tubes'" there is shown in FIG. 1(d) an ω - β diagram which illustrates the transverse (T) and longitudinal (L) modes of the ring-plane circuit of FIG. 1(b). The version of the ring-plane circuit therein discussed comprises a pair of conductive plates, positioned in a common plane, between which are attached a series of spaced conductive rings. In the longitudinal mode, the one ordinarily desired for traveling-wave tube interaction, opposite sides of the rings in any transverse plane of the ring plane circuit are excited in phase whereby predominantly longitudinal electric fields exist between successive rings and on the axis. On the other hand, the transverse mode is characterized by an out-of-phase excitation of opposite sides of the rings which consequent strong transverse electric fields. Thus the ring-plane slow-wave circuit, for example, has at least two modes of propagation having nearly equal phase velocities which makes difficult the excitation of only the desired mode.

2

It is therefore a primary object of the invention to provide a coupling arrangement for coupling to a multi-mode circuit electromagnetic energy in a selected mode.

It is a further object of the invention to terminate reflectionlessly the undesired modes of a multi-mode circuit whereby reflection-induced oscillations are inhibited.

These and other objects of the invention are achieved by providing separate coupling channels to or from separated points of a suitable wave transmission circuit, such as the opposite sides of the plane symmetry of a ring-plane circuit. These separate channels, which thus separately transmit equal portions of electromagnetic energy, are connected to the separate symmetrical ports of a suitable phase-sensitive four-branch microwave network, for example, a magic tee circuit, which directs energy in the different modes to different branches or ports, discrimination among the modes being based upon the relative phasing of the electromagnetic waves.

Thus in its use as an output coupler, the separated energy from the wave transmission circuit is transmitted by the separate coupling channels to the symmetrical ports of the magic tee or other phase-sensitive circuit. Because of the phase difference, the energy of the two modes is separated by the magic tee circuit, the longitudinal or in-phase mode energy appearing at the corresponding asymmetrical port of the magic tee (hereinafter called the H-plane port) while the transverse or out-of-phase mode energy appears at the other asymmetrical port of the magic tee (hereinafter called the E-plane port). The port providing the desired mode (usually the H-plane port) is connected to a utilization circuit while the port corresponding to the undesired mode is ordinarily terminated in a matched load to dissipate the energy of the undesired mode thereby preventing its reflection whereby reflection-induced oscillation is avoided.

In its use as an input coupler, input energy is applied to the asymmetrical port corresponding to the desired mode, the other asymmetrical port being terminated in a matched load. The input energy divides in the magic tee or phase-sensitive circuit. This divided energy appears at the symmetrical ports of the magic tee and is transmitted and applied by the coupling channels to the two sides of the plane of symmetry of the wave transmission circuit or points corresponding to opposite phase relation.

Thus very effective separation and control of the multiple modes is achieved even though they are not widely separated in terms of phase velocity.

The invention is described more specifically with reference to the accompanying drawing in which:

FIGURE 1 is a schematic illustration showing the selective coupler system of the invention as employed with a traveling wave tube;

FIGURE 2 is a perspective illustration of a preferred form of wave transmission circuit;

FIGURE 3 is a perspective illustration of a selective coupler according to the invention; and

FIGURE 4 is a cut-away perspective illustration showing the coupling channels and transition section and their relation to the wave transmission circuit.

FIG. 1 schematically illustrates the use of selective couplers according to the invention as both the input and output coupling means to the wave transmission or slow-wave circuit of a traveling wave tube.

A traveling-wave tube is illustrated schematically in FIG. 1 as comprising an electron gun, including a cathode 10 and a plurality of focusing and accelerating electrodes 11 and 12 for projecting a beam of electrons adjacent a wave transmission or slow-wave circuit 13 to a collector electrode 14. These elements of the traveling-wave tube are enclosed in an evacuated envelope (not shown) and appropriate operating voltages are applied to terminals

15, 16, 17 and 18 connected to respective tube elements. Also it is ordinarily necessary to provide means (not shown) for focusing the electron beam along its path between the cathode 10 and the collector electrode. Such focusing may be accomplished, for example, by a magnet structure providing a magnetic field parallel to the path of the beam.

The wave transmission or slow-wave circuit 13 is characterized as being a two-sided circuit having a longitudinal plane of symmetry and having two modes of propagation within the frequency range of interest, a longitudinal mode wherein the two sides are excited in-phase and a transverse mode wherein the two sides are excited out-of-phase. The coupler of the invention provides the coupling of electromagnetic energy to the slow-wave circuit in a selected mode.

As illustrated in FIG. 1 an input coupler 19 includes a pair of coupling channels 20 and 21 and a four-branch network, illustrated as a magic tee junction 22. The well-known magic tee waveguide junction 22 includes a pair of symmetrical ports 23 and 24 and a pair of asymmetrical ports 25 and 26. (Such magic tee junctions are discussed, for example, by Montgomery et al. in a book entitled "Principles of Microwave Circuits," Radiation Laboratory Series, pages 306 and 452, McGraw-Hill, New York, 1948.)

The magic tee junction has the property of dividing (or combining) microwave energy on the basis of phase relationship and directing the energy of different phase relation (corresponding to different modes) to different ports. In the present coupler structure the asymmetrical port 25, designated the H-plane port, corresponds to the longitudinal or in-phase mode. The asymmetrical port 24, designated the E-plane port, corresponds to the transverse or out-of-phase mode.

Operation of the input coupler 19 is as follows: Input electromagnetic energy is applied from a source 42 to the appropriate asymmetrical port of the magic tee 22 depending upon the mode of excitation desired. In the present example it is assumed that the longitudinal mode is the desired mode. Therefore the input energy is applied from source 42 to the H-plane port 25. The magic tee 22 operates to divide the input energy equally and to thus direct equal portions thereof to the symmetrical ports 23 and 24 and thence into the coupling channels 20 and 21. The coupling channels 20 and 21 include a respective pair of transition sections 28 and 29 by which the divided input energy is applied equally to opposite sides of the slow-wave circuit 13 for propagation thereby. The E-plane port 26 is terminated by a matched load, illustrated as a resistance 27, whereby out-of-phase energy which may appear at this port is absorbed and not reflected into the system.

The output coupler 19' is similar to the input coupler 19 and includes similar elements as indicated by the primed reference numbers. The transition sections 28' and 29' couple the electromagnetic energy from respective sides of the wave transmission circuit 13 into the coupling channels 20' and 21'. The thus separated output energy is applied by the coupling channels 20' and 21' to the symmetrical ports 23' and 24' of the magic tee junction 22'. (It is noted that the coupling channels are formed with equal waveguide lengths from the transition regions adjacent the wave transmission circuit to the symmetrical ports of the magic tee so that the phase relation of divided output energy is maintained.)

Upon receipt of the divided output energy by symmetrical ports 23' and 24', the magic tee junction 22' operates to combine the energy according to its phase relation by which the in-phase energy is directed to the H-plane port 25' and any out-of-phase (or transverse mode) energy is directed to the E-plane port 26'.

The H-plane port 25' is connected to a utilization circuit 43. The E-plane port 26' is terminated in a matched load, represented as a resistor 27' in FIG. 1, by which

reflection of the transverse mode energy is substantially prevented to thereby prevent reflection-induced oscillations in the system. The energy from the E-plane port may, of course, be otherwise utilized if desired.

5 The wave transmission circuit 13 of FIG. 1 may advantageously comprise a ring-plane slow-wave circuit 313 as illustrated in FIG. 2. Such a slow-wave circuit includes a pair of spaced conductive plates or strips 30 and 30' which form a plane of symmetry and between which are attached a plurality of spaced conductive rings 31(1)-31(n). Further discussion of this circuit may be found in the previously mentioned White et al. article and in the references therein cited, it being sufficient for present purposes to observe that this circuit can advantageously be employed in a traveling wave tube for the desired high frequency and high power operation and that it supports two modes as illustrated by the ω - β diagram of FIG. 1(d) of the foregoing article.

FIG. 3, is a perspective illustration of the selective coupler of the invention. As illustrated in FIG. 3, a selective coupler 319 comprises a pair of coupling channels formed by waveguides 320 and 321, a magic tee waveguide junction 322 having symmetrical ports 323 and 324 and asymmetrical ports 325 and 326, and a pair of transition sections 328 and 329 for coupling the coupling waveguides 320 and 321 to a wave transmission circuit 313.

Shown in FIG. 4 is a partly cut away view showing the interior of the coupling waveguides 320 and 321 of FIG. 3 and illustrating in more specific detail a preferred form 30 of the transition sections 328 and 329. The transition section 329, for example, includes opposing surfaces 40 and 41 which form a curved, tapering transition section by which electromagnetic energy is launched upon, or received from, the respective side of the wave transmission circuit 313.

35 Thus what has been described is a selective coupler structure for coupling electromagnetic energy in a selected mode to a multimode wave transmission circuit while suppressing excitation of undesired modes whereby such multimode wave transmission circuits may be advantageously employed in a high-frequency, high-power traveling-wave tube or the like.

Although the invention has been described with reference to an illustrated embodiment of a multimode wave 45 transmission circuit having a single plane of symmetry, the principles of the invention as taught herein may be extended and applied to wave transmission circuits having a plurality of planes of symmetry such as shown, for example in FIG. 1(c) of the previously mentioned White et al. article.

50 While the principles of the invention have been made clear in the illustrative embodiments, there will be obvious to those skilled in the art, many modifications in structure, arrangement, proportions, the elements, materials, and components, used in the practice of the invention, and otherwise, which are adapted for specific environments and operating requirements, without departing from these principles. The appended claims are therefore intended to cover and embrace any such modifications within the limits only of the true spirit and scope of the invention.

55 What is claimed is:

1. The combination of: a two-sided slow wave transmission circuit having a longitudinal plane of symmetry, 65 thereby providing two modes of propagation of electromagnetic energy, a first mode characterized by being in phase with respect to the two transverse sides of the plane of symmetry of said circuit and a second mode characterized by being out-of-phase with respect to said two sides; a pair of coupling channels adapted to separately receive electromagnetic energy from respective sides of said circuit; and an electromagnetic wave network having four branches for receiving energy from said coupling channels at first and second branches and for directing energy in said first mode to a third one of said 70 75

branches and for directing energy in said second mode to a fourth one of said branches.

2. The combination of: a two-sided slow wave transmission circuit having a longitudinal plane of symmetry, thereby providing two modes of propagation of electromagnetic energy, a first mode characterized by being in phase with respect to the two transverse sides of the plane of symmetry of said circuit and a second mode characterized by being out-of-phase with respect to said two sides; a four branch electromagnetic wave network for receiving electromagnetic energy in a predetermined mode at a respective first branch and to direct said energy equally to second and third branches; and a pair of coupling channels for coupling said energy from said second and third branches separately to respective sides of said wave transmission circuit.

3. The combination of: an elongated two-sided slow wave transmission circuit having a longitudinal plane of symmetry, thereby providing propagation of electromagnetic wave energy in transverse and longitudinal modes; an electromagnetic wave network having first and second branches symmetrical to each other and having a third branch corresponding to said transverse mode and a fourth branch corresponding to said longitudinal mode, said third and fourth branches being asymmetrical to each other, said network directing to said symmetrical branches equal portions of electromagnetic energy applied to a selected one of said asymmetrical branches in a corresponding mode, and directing electromagnetic energy received at said symmetrical branches to said asymmetrical branches according to its mode; and a pair of coupling channels forming separate electromagnetic en-

- 5
10
15
- ergy coupling circuits between said symmetrical branches of said network and said wave transmission circuit.
4. A circuit adapted for slow-wave transmission of electromagnetic wave energy between a source and a utilization circuit, comprising: a two-sided slow wave transmission circuit having a longitudinal plane of symmetry, thereby propagating electromagnetic wave energy in transverse and longitudinal modes; a mode-selective input coupling circuit for launching said wave energy from said source upon said wave transmission circuit; and a mode-selective output coupling circuit for coupling wave energy from said wave transmission circuits to said utilization circuit, said output coupling circuit including a pair of coupling channels transmitting equal portions of wave energy from separated points on said wave transmission circuit, and a four-branch phase-sensitive network for receiving said equal portions of wave energy from said coupling channels at respective ones of two of said branches, for directing the wave energy in said longitudinal mode to a third one of said branches and for directing the wave energy in said transverse mode to a fourth one of said branches.
